CURT FREDERICK REIS, OF CHICAGO, ILLINOIS, ASSIGNOR TO EXCEL MAGNETO COMPANY, OF CHICAGO, ILLINOIS

MAGNETO MOUNTING AND CONNECTION

Application filed July 2, 1930. Serial No. 465,439.

This invention relates to internal combustion engines and especially those of the "Diesel" type in which the fuel is injected into the cylinders and ignited by compression rather than by an electric spark as is common in the more conventional types of internal combustion engines.

Considerable difficulty is encountered in starting the Diesel type of engine by reason 10 of the high pressures necessary to ignite the cylinder charge, and it has been attempted to overcome this difficulty by employing an electric circuit and conventional spark plugs to start the engine and thereafter shutting off 15 the current. Such prior devices have been objectionable because uneconomical and for various other reasons which need not be enumerated herein.

An object of the present invention resides 20 in the provision of a movably mounted generator which may be moved into operative relation with a Diesel engine when the latter is to be started and thereafter moved to an inoperative and inactive position.

Another object of the invention consists in 25 providing in combination with a Diesel engine and a movably mounted magneto, a coupling which is so designed as to permit the coupling of the magneto shaft with the engine at only one position relative to the gearing of the engine, thereby providing for the proper timing of the ignition system.

Other objects and advantages of the invention will be apparent from the following description when taken in connection with the accompanying drawing, in which

Figure 1 is a more or less diagrammatic representation of a Diesel engine in combination with a slidably mounted magneto and 40 a suitable coupling between them.

Figure 2 is a horizontal sectional view through the magneto mounting, looking in the direction of the arrows.

Figure 3 is a detail perspective view of the 45 two members of the coupling; and

Figure 4 is an end view of one of the coupling members.

Referring to the drawing in more detail the numeral 1 indicates generally an internal 50 combustion engine of the high compression

or Diesel type, the timing gear for which is indicated generally by the numeral 2.

Mounted on one side of the engine body or in any other position adjacent the timing mechanism 2 is a bracket 3 anchored to the engine by means of bolts 4. This bracket in the embodiment here shown is provided with four slots 5 adapted to receive bolts 6 which are passed up from the underside of the bracket and fixed in a plate 7 secured to a magneto 8. It will be obvious, therefore, that the magneto may be moved longitudinally of the bracket 3 a distance equivalent to the difference between the length of the slots and the diameters of the bolts 6.

The magneto 8 is of any preferred construction and provided with a rotor shaft 9. To the outer end of shaft 9, i. e. the end adjacent the timing gear 2, is secured a coupling member 10 consisting of a socket portion 11 which is directly connected to the shaft 9 and a disc portion 12 provided with a plurality of recesses 13 and 14; there being indicated in the drawing three recesses 13 of rectangular formation and a single recess 14 of cylindrical formation.

On the shaft 15 of the engine timing gear 2 is secured a complementary coupling member 16 comprising a socket portion 17 fixed to the shaft 15 and a disc portion 18. The face of the disc portion 18 is provided with a plurality of lugs 19 and 20; there being three lugs 19 of a shape corresponding to the recesses 13 in disc 12, and a cylindrical lug 20 corresponding to the recess 14 in disc 12. It will thus be apparent that the coupling or clutch members 10 and 16 can only be engaged when the cylindrical lug 20 is in alignment with the cylindrical recess 14. By this arrangement it will be obvious that the shafts 9 and 15 are always in the same relative angular positions when the coupling members 10 and 16 are in operative engagement.

As stated hereinbefore, one of the primary objects of the present invention is to provide a magneto in conjunction with an internal combustion engine which may be uncoupled from the operating parts of the internal combustion engine after the engine is started, and remain idle until such time as it is again 100

desired to start the engine. For the purpose of uncoupling or throwing out of operation the magneto, any preferred mechanism may be employed to slide the same on its mounting 6 in a direction to disengage the coupling members 10 and 16. In the present embodiment of the invention I have provided a boss 21 on a side of the magneto casing to which is connected a link 22. This link has its opposite end connected to one arm of a bell crank lever 23 suitably mounted on the vehicle structure or other structure with which the engine is associated. The other arm of this bell crank may be connected with a link 24 which is in turn connected with a bell crank lever 25 operable from the dash or other convenient point by means of a pull rod 26. It will thus be apparent that by the simple operation of the plunger 26 the rotor shaft of the magneto may be engaged with or disengaged from the timing shaft 15 of the engine. It is essential, of course, that each time the rotor of the magneto is connected with the timing shaft of the engine the same relative positions of the two shafts are maintained in order to retain the proper timing of the spark plugs in the various cylinders. This end is accomplished by means of the design of the several lugs and recesses on the coupling members 10 and 16, as heretofore referred to. Of course, the proper relative positions of the shafts might be attained by having only a single lug on one coupling member and a single complementary recess on the other coupling member. However, in order to properly distribute the torque and thus prolong the life and usefulness of the apparatus, it is desirable that the coupling members be engaged at a plurality of points. It is for this reason that three lugs and recesses of identical construction are shown and a single lug and recess of a different construction are employed. It is to be understood, however, that a greater or fewer number of these lugs and recesses may be employed as desired. From the foregoing description taken in connection with the accompanying drawing, it will be apparent to those skilled in the art that I have provided a mounting for magnetos and a releasable coupling between the rotor shaft thereof and the timing gear of an internal combustion engine; that the mounting is so designed as to permit of a relative movement between the magneto and the timing shaft of the engine so as to engage or disengage the coupling between these shafts; that means are provided for readily moving the magneto to operative and inoperative positions; and that the coupling is so designed as to maintain at all times the proper relative angular positions of the rotor shaft and the engine timing shaft when the coupling members are operatively connected, thereby insuring the proper timing of the sparks for

the various cylinders whenever the magneto is coupled to the timing shaft.

In accordance with the patent statutes I have described what I now believe to be the preferred form of the invention, but inasmuch as various minor changes may be made in the details of construction without departing from the essence of the invention it is intended that all such changes be included within the scope of the appended claims. 75

What I claim as new is:

1. In an internal combustion engine, a movably mounted magneto, a coupling between the magneto shaft and the engine gearing, said coupling being constructed and arranged to cause said shaft to assume the same angular relation to the engine gearing when coupled thereto, and means for moving said magneto to coupling and uncoupling positions. 80

2. In an internal combustion engine, a movably mounted magneto, a coupling member fixed to the magneto shaft, a coupling member fixed to the timing gear of the engine, complementary lugs and recesses formed on the respective coupling members, said lugs and recesses being so designed as to cause them to assume the same relative angular position when engaged, and means for moving said magneto to cause the engagement or disengagement of said members. 85

3. In an internal combustion engine, a slotted bracket mounted thereon, a magneto slidably mounted on said bracket through engagement with said slots, a releasable coupling between said magneto and the timing gear of the engine, and means for moving said magneto to release or engage said coupling. 90

4. Means for releasably connecting the rotor shaft of a magneto with the timing shaft of an engine, said means comprising a disc fixedly secured to each of said shafts, a plurality of lugs formed on the face of one of said discs, one of said lugs being of an odd shape, the other disc provided with a complementary series of recesses to receive said lugs, and means for causing a relative movement between said discs to cause their engagement or disengagement. 105
